WARREN S. BELLows, OF EAST ORANGE, NEW JERSEY

FOLDING TABLE

Application filed March 5, 1925. Serial No. 13,089.

This invention relates to folding tables for domestic use, as well as for use in hotels, restaurants, business offices, and other places where an article of this kind may be in demand.

It is an object of this invention to provide a folding table which can be easily and cheaply constructed from a small number of easily formed parts and which will have all the rigidity and strength of the non-folding present-day tables.

A particular object of the invention is to provide a folding table in which the legs are braced in two directions substantially parallel with the rim of the table and in which said braces fold with the legs to folded or upright position.

Another object of the invention is to provide a folding table of the type described, in which the legs and braces are supported from the rim of the table, thereby permitting the use of relatively light and cheap material in the top of the table without sacrificing the strength or rigidity of the table.

Another object of the invention is to provide a folding table in which the legs may be formed of ordinary angle-iron construction and in which, when folded, the leg braces are enclosed between the angle of the leg and the top of the table.

Another object of the invention is to provide a folding table with support braces extending diagonally across each corner and joining the rim of the table along each side, said support braces providing means for supporting the leg braces and increasing the strength and rigidity of the rim and legs of the table regardless of the strength or construction of the table top.

Various other objects and advantages will appear as the description of the invention proceeds.

Referring now to the drawings, which illustrate several preferred forms of embodiment of the invention,—

Fig. 1 is a bottom plan view, partially in section, showing the folding table with the legs thereof in both folded and unfolded position;

Fig. 2 is a sectional view on the line 2—2

of Fig. 1, showing the leg and braces in unfolded position and showing the position these braces assume when the leg is being folded toward the table top;

Fig. 3 is a sectional view on the line 3—3 of Fig. 1, showing one of the legs in unfolded position;

Fig. 4 is a fragmentary detail bottom plan view of one corner of the table;

Fig. 5 is a detail view illustrating how the leg is pivoted to the rim of the table;

Fig. 6 is a sectional view on the line 6—6 of Fig. 1, illustrating how the leg folds into contact with the rim and top of the table and covers the braces;

Fig. 7 is a broken plan view of a modified form of the invention;

Fig. 8 is a sectional view on the line 8—8 of Fig. 7;

Fig. 9 is a sectional view on the line 9—9 of Fig. 7;

Figure 10 is a view of a modified form of the invention;

Figure 11 is a detail view showing one of the legs and braces illustrated in Figure 10 in unfolded or upright position;

Figure 12 is a sectional view on the line 12—12 of Figure 11;

Figure 13 is a detail view of a modification of the angle iron legs;

Figures 14 and 15 are sectional views on lines 14—14 and 15—15, respectively, of Figure 11.

Figure 16 is a detail view of a modified form of angle iron leg.

In the preferred form of embodiment of the invention the table comprises a rim 1 of comparatively strong and rigid material which may be of wood or metal. The top 2 is supported on the rim 1, and in each corner of the rim, a brace support 3 extends diagonally from one side of the rim to the other and is turned up at 3^a on each end, and the portion 3^a secured to the rim 1 by means of screws, rivets, welding, or the like 4.

At each corner of the rim 1 a bracket 5 is secured and inside these brackets, the angle iron legs 6 of the table are pivoted by means of a pivot bolt 7, which extends through the rim 1 of the table and through one side of the

angle iron leg 6 so as to permit the leg to be turned round the pivot 7 from upright to folded position. The brace 3 has struck out therefrom a pair of ears 8 and 8^a which are located in line with the leg and in planes substantially at right angles to each other. The brace 9 extends from the ear 8^a parallel to the adjacent rim 1 of the table to the leg 6 where it is bent slightly into an ear 9^c extending for a short distance along the leg, and is joined to the leg by means of a suitable rivet 9^a. The rivet 9^b, which joins the brace 9 to the ear 8^a, is in line with the pivot bolt 7 which secures the leg to the rim of the table and permits the brace 9 to turn around rivet 9^b when the leg 6 is turned around the pivot bolt 7. The rivet 9^a also secures one end of the leg 10^a of the jack knife brace 10 to the leg of the table while the other end of the leg 10^b of this brace is pivoted to the ear 8 of the support brace 3, the end of the leg 10^a being spaced from the leg 6 by the ear 9^c. The legs 10 and 10^c of the jack knife brace 10 are pivoted together by means of a rivet 11 which is located so as to permit proper folding of the legs and braces. The lug 10^c prevents the brace 10 from collapsing inwardly when the leg is moved to unfolded or upright position, and a hole 10^d and pin 10^e serves to lock the parts of the brace 10 in unfolded position to prevent collapse thereof. The location of the rivet 11 permits the leg 6, when the jack knife brace is broken, to fold inwardly toward the table top, the two legs 10^a and 10^b of the brace folding alongside each other, as illustrated in Figure 1, and the ear 9^c brings the brace 9 slightly nearer to the corner of the table at which the leg is pivoted than the ear 8 and the brace 9 folding with the leg, folds inside the ear 8, thereby permitting the leg 6 to fold flush with the bottom of the rim 1 of the table, with the braces, ears, supports and other securing means between the upper angle of the angle iron leg 6 and the table top. The ears 3^a of the support 3 and the angle iron brackets 5 space the legs 6 away from the rim of the table so as to permit free folding of the leg. When in unfolded position, the braces 9 and 10 extend substantially parallel with the adjacent rims of the table, and brace the legs in a direction at right angles to each other so as to form a very rigid table supporting construction, while the diagonal braces 3 extend from rim to rim forming a very rigid rim structure, regardless of the strength of the material of which the top 2 is formed. This rigid leg and rim structure may advantageously be used with the detachable tops described in my co-pending application Serial No. 719,514 filed June 12, 1924 if so desired. At the same time these braces fold with the legs into the space between the outer edge of the legs and the top of the table so that they do not increase the thickness of the fold-

ed table, and only one operation is necessary to simultaneously fold and unfold both the legs and the braces.

In the form of the embodiment of the invention illustrated in Figs. 7 to 9, the leg 20 of the table is preferably of square cross section and may be formed from wood or from tubular metal or other suitable material. The leg is spaced from the corner of the meeting edges of the rim 1 and is spaced from the portion of the rim 1 to which it is pivotally secured by the bolt 21 by means of a spacing washer 21^a. The supporting braces 22 which support the leg braces 23 and 24, extend diagonally across each corner of the table and are connected as by means of screws 22^a to the rim of the table. Ears 23^a and 24^a are struck up from the supporting brace 22 so as to lie in planes substantially at right angles to each other, and the folding brace 23 is pivoted to the ear 23^a, while the jack knife brace 24 is pivoted to the ear 24^a, so that each of these braces extends at substantially right angles to the other and brace the leg 20 in two directions, while at the same time permitting the leg and the braces to be folded into the space formed by the table top and the rim when the table is not in use. The jack knife brace is similar to that illustrated and described in Figs. 1 to 6, and operates in substantially the same way.

The spacing of the legs 20 from the corner of the table in this embodiment of the invention permits square or other shaped legs to be used without having the braces and especially the ears 23^a and 24^a from interfering with the folding of the legs flush with the table top. Only an angle iron leg could fold over the ear 8^a as illustrated in Fig. 6.

Figure 10 is a view similar to Fig. 1 of a folding table comprising a rim 1^a, a top 2^a, and provided with a plurality of angle iron legs 6^a which, when not in use, fold to a position along the rim of the table. The legs 6^a are pivoted to the table by means of a pivot bolt 7^a which extends through one side of the leg 6^a and through a spacing block 12, and is secured at the other end in a bracket 12^a which is secured to both the top and rim of the table. A V-shaped brace 13 has each leg thereof pivoted at 13^a to bracket 3^b secured to the rim of the table so that when the brace is in unfolded position, each of the legs 13^b and 13^c extend substantially parallel with the adjacent rim of the table, and brace the leg 6^a in two directions which are substantially at right angles to each other. The apex or ends 14 of the braces 13 are bent as illustrated at 14^a so as to lie substantially parallel with the legs 6^a when the legs are in unfolded position, and are connected together at the bent portion 14^b by means of a clamping attachment 15, which embraces each leg of the portion 14^b and provides an opening 15^a through which a locking pin 16 may be inserted to hold

the brace and leg in unfolded or upright position. The legs 6^a are provided with a pair of spaced eyes 17 which fit into the angle of the leg, and, in unfolded position, are in alignment with the opening 15^a in the clamping member 15 and between which the clamping member is received, so that, when the pin 16 is pushed through these aligned openings, the brace and leg are securely locked in unfolded position, with the legs, of the brace extending at substantially right angles to each other. The end of the angle iron legs 6 or 6^a is preferably closed by means of a section 6^b which is formed from one side of the leg 6 and folded over to form a smooth bottom 6^c for the leg, which may have a suitable coaster or skid 18 applied thereto to prevent injury to the floor or floor covering upon which the table may be used. Spring clips 13^a secured to the top 2 of the table hold the braces 13 in folded position when not in use. If desired the braces 13 may be pivoted to supports which extend diagonally across the corner of the table as do the braces 3. Figure 13 shows a light angle iron leg 6^d reinforced with a wood filler 6^e, giving light weight and strength to the leg.

For extremely long tables it may be desirable to provide additional legs at about the midpoint of the sides of the table and in the form of embodiment illustrated in Fig. 10, this may be done by providing a bracket 12^b at about the midpoint of the rim 1^a to which the leg 6^d may be pivoted, so as to swing to either side parallel to the rim of the table. Braces 13^d, similar to braces 13, may be pivoted to the table top so as to fold flat therewith when not in use.

Figure 16 shows a modified form of angle iron leg 19 in which one side of the angle 19^a is cut away at each end and the other side 19^b is curled around to form circles 19^c the circle at one end being adapted to embrace the spacing member 12 and to turn on the spacing member as a pivot, while the circle member 19^c at the other end presents a rounded and smooth base upon which the leg may rest on the floor.

In compliance with the patent statutes, I have illustrated and described several forms of embodiment of my invention, but it is to be understood that various modifications and changes can be made in the embodiments of the invention herein disclosed without departing from the spirit of the invention or the scope of the appended claims.

I claim:

1. In a folding table of the type described a table top, a rim, rim bracing members extending from one side of said rim to the other, legs pivotably supported from said rim and leg braces extending between the legs and bracing members and pivoted to said leg bracing members, one of said leg braces being collapsible to permit said legs and leg braces

to fold to a position substantially parallel with the table top.

2. In a folding table of the type described, a table top, a rim around said top, bracing members extending diagonally across the corners of said table and connected to adjacent sides of the rim, legs pivoted to said rim, leg braces pivoted to said bracing members and in unfolded position connected to said legs and bracing the same in two directions substantially at right angles to each other, one of said leg braces being centrally pivoted, said legs and leg braces being foldable to a position substantially parallel with the table top.

3. In a folding table of the type described, a table top, a rim around said top, bracing members extending diagonally across the corners of said table between adjacent sides of said rim, legs pivoted to said rim, a pair of leg braces pivoted to each of said bracing members and connected to said legs and bracing the same in two directions substantially parallel with the sides of said rim, one of said leg braces being foldable with the legs to a position substantially parallel to the table top.

4. In a folding table of the type described, a table top, a rim around said top, bracing members extending diagonally across the corners of said table between adjacent sides of said rim, angle iron legs pivoted to said rim, a pair of leg braces pivoted to each of said bracing members and connected to said angle iron legs and bracing the same in two directions substantially parallel with the sides of said rim, said legs being foldable to a position substantially flush with the bottom of said rim and said leg braces being foldable with the legs to a position between one angle of the legs and the table top.

5. In a rectangular folding table, a rim, an angle iron leg pivoted to the rim at each corner, a supporting brace extending diagonally across each corner and connected to the rim at each end, a leg brace pivoted at one end on said supporting brace in alignment with said leg pivot and connected at the other end to said leg, a second leg brace pivoted at one end to said leg and at the other end to said supporting brace and extending substantially perpendicular to said first leg brace said second brace being collapsible so that both leg braces fold with the leg to folded or unfolded position.

6. In a rectangular folding table, a rim, angle brackets at each corner of said rim, an angle iron leg pivoted to the rim in each bracket, a supporting brace extending diagonally across each corner and connected to the rim at each end, a leg brace pivoted on one end on said supporting brace in alignment with said leg pivot and connected at the other end to the inside of said leg, a jack-

knife leg brace pivoted to the leg at one end and at the other end to said supporting brace and lying in a plane substantially perpendicular to the plane of said first leg brace, 5 said second brace being collapsible so that both leg braces fold with the leg.

7. In a rectangular folding table, a rim, an angle iron leg pivoted to the rim at each corner, a supporting brace extending diagonally across each corner and connected to the rim at each end, a leg brace pivoted at one end on said supporting brace in alignment with said leg pivot and connected at the other end to said leg inside the angle 10 thereof, a second leg brace pivoted at one end to said leg inside the angle thereof, and at the other end to said supporting brace and extending substantially perpendicular to said first leg brace said second brace being collapsible so that both leg braces fold with the 15 leg to folded or unfolded position.

In testimony whereof I have affixed my signature to this specification.

WARREN S. BELLOWES.
